UNITED STATES PATENT OFFICE.

EMANUEL GARNER, OF STOCKPORT, ENGLAND.

APPARATUS FOR BLOCKING HATS.

No. 863,375.

Specification of Letters Patent.

Patented Aug. 13, 1907.

Application filed May 18, 1907. Serial No. 374,512.

To all whom it may concern:

Be it known that I, EMANUEL GARNER, subject of the King of Great Britain and Ireland, and residing at 196 Turncroft Lane, Stockport, in the county of Chester, England, have invented new and useful Improved Apparatus for Blocking Hat-Bodies Made of Felt, Straw, or the Like, of which the following is a specification.

This invention relates to improved apparatus for blocking hat bodies of any suitable material.

10 In the accompanying drawing illustrating my said invention, and to which I hereinafter refer, Figure 1 is a side view, Fig. 2 a plan and Fig. 3 an end elevation of apparatus constructed according to this my said invention as seen when not in work. Fig. 4 is a side view of 15 the same apparatus in operation. In these views the same letters refer to like parts.

According to my invention I propose to use hydraulic pressure for this purpose. The wooden block *a* for the hat body is fixed on a metal plate *b* carried at the top of 20 the ram *c* of the press which works through a stuffing box *d* placed at the top of the hydraulic cylinder *e*. The hollow metal dish *f* for the hat is attached to a top frame as *g* which is supported by columns or brackets as *g'* and *g''* above the center of the ram either as shown 25 or in any convenient manner.

The hat body to be blocked is placed upright on the wooden block *a* and a ring *j* of india rubber of suitable

thickness is placed above the brim, water under pressure is then admitted into the cylinder *e* causing the ram to rise and press the hat body into the interior of 30 the hollow metal dish *f* which is fixed above the wooden block *a* as before described. When the hat body has remained thus under pressure for the requisite time the head of water is allowed to escape and the ram with the wooden block and pressed hat body will descend to its 35 former position, so that the pressed hat body can be removed from the wooden block, and a fresh hat body substituted and treated in a like manner.

I may in some cases prefer to construct the apparatus with the ram placed above the hat body, and the 40 blocking device inverted which would obviously be the same invention.

I claim as my invention:—

An improved apparatus for blocking hat bodies, comprising a hydraulic ram *c*, a block *d* for the hat body fixed on a 45 metal plate on the end of the ram, a ring of india rubber *j* and a hollow metal dish *f* attached to a frame *g*, all substantially as hereinbefore described and shown on the accompanying drawings.

In testimony whereof I have signed my name to this 50 specification, in the presence of two subscribing witnesses.

EMANUEL GARNER.

Witnesses:

THOS. PRESCOTT,
J. ERNEST HUGHES.
